UNITED STATES PATENT OFFICE

FREDERICK CHARAVAY, OF PIQUA, OHIO, ASSIGNOR OF ONE-HALF TO HARTZELL INDUSTRIES INC., OF PIQUA, OHIO, A CORPORATION OF OHIO

METAL TIPPING FOR PROPELLERS

Application filed June 4, 1929. Serial No. 368,258.

This invention relates to new and useful improvements in metal tipping for airplane propellers.

It is the principal object of my invention 5 to provide a combination hard and soft metal tip for wood airplane propellers. A hard metal such as Monel, may be easily punched, but it is drilled with difficulty. However, when the hard metal is used only 10 on the face of the propeller, where it is most needed, and a soft metal such as brass is employed on the back side where there is little wear, the two metals may be easily riveted to the thin propeller tip by first punching the 15 hard metal. The drill is then started through the latter, the propeller tip and the brass piece on its back side to provide holes to receive the rivets.

Such a propeller tip is armored with the 20 hard metal on its face where it strikes weeds, stones and cinders, and with soft metal on its rear side where there is little wear. Furthermore, economy of manufacture is promoted by the use of soft metal with the hard, since 25 the latter is more expensive, and when used on both sides of the tip increases the cost of its production.

It is another object of my invention to 30 provide a soft metal strip, such as brass, along the leading edge of the rear portion of the wood propeller, with a serrated section of hard metal along that portion of the leading edge of the propeller where its velocity is high and where it is more exposed to the elements such as rain.

Other important and incidental objects 35 will be brought out in the following specification and particularly set forth in the subjoined claims.

In the accompanying drawings illustrating 40 my invention, Figure 1 is a view of the rear side of my improved propeller. Figure 2 is a cross sectional view taken through the same on the line 2—2 of Figure 1, showing 45 how the hard and soft metal tips are secured thereto. Figure 3 is an enlarged cross sectional view taken through the tip end of the propeller, showing how the hard metal strip is lapped over the soft metal one. Figure 4 50 is a cross sectional view taken through the

propeller on the line 4—4 of Figure 1, showing how the serrated hard metal strip is screwed over the middle front part of the leading edge of the propeller. Figure 5 is a plan view of the hard metal strip attached to the propeller. And Figure 6 is a plan view of the soft metal piece attached to the propeller tip.

Referring to the accompanying drawings 55 for a detailed description of my invention, the numeral 1 designates one end of a wood propeller of aerofoil section. The propeller is tipped with two metal strips, one of hard metal and the other of soft metal, to reduce the cost of production without impairing the 60 efficiency of the propeller.

Referring to Figure 5, the numeral 2 designates a metal blank preferably of Monel metal, with a wide tapered head portion 3 and an elongated, serrated tail portion 4. In 65 Figure 6 there is shown a blank 5 of soft metal, preferably brass.

The brass strip 5 is first applied to the rear 70 face of the propeller tip and bent over its leading edge, after which the Monel metal strip 2 is applied to the front face of said tip. The head portion 3 of the Monel metal strip 2 is then lapped over the brass strip 5 and soldered to the latter as shown in Figures 1, 2 and 3.

Holes are punched in the head portion 3 75 of the Monel metal strip 2 after which a drill is started through those holes, the thin propeller tip and the brass strip 5. Rivets 6 are then inserted in said holes and their heads 80 soldered over. (See Figures 1, 2 and 3.)

Through the holes 7 in the tail portion 4 of the Monel metal strip 2, screws 8 are inserted for passage into the propeller after 85 said strip is bent over its leading edge.

Over the leading edge of the propeller 1, behind the Monel metal strip 2, a brass strip 9 is secured by screws. These screws, as well as the screws 8, are soldered over to make the surface of the brass and Monel metal 90 strips uniformly smooth.

The application of the Monel metal to the 95 face of the propeller tip and to that portion of its leading edge immediately behind the tip reinforces it for the severe wear to which 100

it is subjected through contact with stones, weeds and cinders and exposure to rain. The rear face of the tip, not being exposed so much to the wearing action just referred to, is covered with a softer and cheaper metal such as brass which may also be easily drilled.

The tail portion 4 of the Monel strip 2, which is serrated to prevent buckling when the propeller vibrates, protects the leading 10 edge of the latter at the points where its velocity is high. Behind these points, the leading edge is covered by the softer and cheaper strip 9.

The propeller end (not shown) on the 15 other side of the hub is tipped and covered at its leading edge in the same manner as the end which has just been described.

Having described my invention, I claim:

1. A wood propeller of aerofoil section, 20 having a combination hard metal and soft metal tip at each end.

2. A wood propeller of aerofoil section, having a combination hard metal and soft metal tip at each end, the hard metal being 25 on the face side of the propeller, and lapping over the soft metal which is on the back side of said tip.

3. A propeller comprising a wood unit of aerofoil section, a brass strip applied to the 30 back face of each tip of said propeller and bent over its leading edge, and a nickel and copper alloy strip applied to the front face of each tip, and lapped over the brass strip.

4. A propeller comprising a wood unit of 35 aerofoil section, a soft metal strip applied to the back face of each tip of said propeller, a hard metal strip applied to the front face of each tip and lapped over the soft metal strip, and rivets passing through the hard metal 40 strip, propeller and soft metal strips for securing said metal strips to their respective propeller tips.

5. A propeller comprising a wood unit of aerofoil section, a soft metal strip secured to 45 the back face of its tip, a hard metal strip secured to the front face of said tip, and lapped over its leading edge, and having a serrated portion projecting over the leading edge a short distance behind said tip, and a soft 50 metal strip secured over the leading edge of said propeller behind the hard metal strip.

6. In a propeller blade, a tipping therefor comprising a continuous strip of metal embracing a part of one edge of the blade, and a 55 continuous strip of a different metal embracing another part of the same edge of the blade, one end of one strip contacting an end of the other strip.

7. In a propeller blade, a tipping therefor 60 comprising a continuous strip of hard metal embracing a part of one edge of the blade, and a continuous strip of a softer metal embracing another part of the same edge of the blade, one end of one strip contacting an end of the 65 other strip.

8. In a propeller blade, a tipping therefor comprising a continuous strip of hard metal embracing a part of one edge and the face side of the tip of the blade, and a continuous strip of a soft metal embracing another part 70 of the same edge of the blade, one end of one strip contacting an end of the other strip.

9. In a propeller blade, a protector therefor comprising a strip of nickel and copper alloy, and a strip of brass covering a leading 75 edge of the blade, the strip of nickel and copper alloy covering that part of the blade most subject to wear.

10. In a propeller blade, a protector therefor comprising a strip of nickel and copper 80 alloy covering a leading edge and the face side of the tip of the blade.

11. In a propeller blade, a protector therefor comprising a strip of nickel and copper alloy covering a leading edge and the face 85 side of the tip of the blade, and a brass strip covering the back side of the tip.

12. In a propeller blade, a protector therefor comprising a strip of brass covering the back side of the tip of the blade, and a strip 90 of nickel and copper alloy covering a leading edge and the face side of the tip and overlapping the edges of the strip of brass.

In testimony whereof I have hereunto set my hand this 31st day of May, 1929.

FREDERICK CHARAVAY.
